UNITED STATES PATENT OFFICE.

ALBERT S. FILSON, OF LOS ANGELES, CALIFORNIA.

DESIGN FOR A WATCH-CHAIN.

41,737.

Specification for Design.

Patented Sept. 5, 1911.

Application filed July 13, 1911. Serial No. 638,385. Term of patent 3½ years.

To all whom it may concern:

Be it known that I, ALBERT S. FILSON, a citizen of the United States, residing at Los Angeles, in the county of Los Angeles and State of California, have invented a new, original, and ornamental Design for Watch-Chains, of which the following is a specification, reference being had to the accompanying drawing, forming part thereof.

The figure is an elevation of the watch-chain, showing my new design.

I claim:

The ornamental design for a watch-chain, as shown.

In testimony whereof, I have hereunto set my hand at Los Angeles, California, this 7th day of July 1911.

ALBERT S. FILSON.

In presence of—

ARTHUR P. KNIGHT,
GLADYS RUSSELL.
